QUILTED FABRIC APPLIQUE BLOCK

Mary Louise Brion, 415 High St.,
Bethlehem, Pa. 18018

Filed Apr. 25, 1974, Ser. No. 464,139

Term of patent 14 years

Int. Cl. D5—04

U.S. Cl. D33—9 D

The figure is a top plan view of a quilted fabric applique block showing my design with all dashed lines representing stitching.

The quilted fabric applique block is of conventional thickness.

I claim:

The ornamental design for a quilted fabric applique block, as shown and described.
